(57) **CLAIM**

The ornamental design for a display screen with animated graphical user interface for determining price competitiveness, as shown and described.

DESCRIPTION

FIG. 1 is a front view of a display screen with animated graphical user interface for determining price competitiveness;

FIG. 2 is second view thereof;

FIG. 3 is third view thereof;

FIG. 4 is a fourth view thereof;

FIG. 5 is a fifth view thereof; and,

FIG. 6 is a sixth view thereof.

The appearance of the graphical user interface transitions between the images shown in FIGS. 1-6. The process or period in which one image transitions to another forms no part of the claimed design.

The broken lines showing the text, the remainder of the graphical user interface and the display screen are for the purpose of illustrating portions of the article, and form no part of the claimed design.
